CLAIM

The ornamental design for a cap insert, as shown and described.

DESCRIPTION

FIG. 1. is a perspective view of a cap insert showing my new design, and with the cap insert having a tab shown in a closed tab configuration;

FIG. 2. is a top plan view thereof;

FIG. 3. is a bottom plan view thereof;

FIG. 4. is a front elevation view thereof;

FIG. 5. is a rear elevation view thereof;

FIG. 6. is a left side elevation of FIG. 1, with the right-side elevation view being a mirror image thereof;

FIG. 7. is another perspective view of the cap insert shown in use in environment on a pharmaceutical waste container;

FIG. 8. is an exploded perspective view of FIG. 1, showing the cap insert having the tab shown in an opened tab configuration;

FIG. 9. is a top plan view thereof;

FIG. 10. is a bottom plan view thereof;

FIG. 11. is a front elevation view thereof;

FIG. 12. is a rear elevation view thereof;

FIG. 13. is a left side elevation view thereof;

FIG. 14. is a right-side elevation view thereof; and,

FIG. 15. is another exploded perspective view of the cap insert shown in use in environment on the pharmaceutical waste container.

The broken lines in the drawing of the pharmaceutical waste container and the cap insert shown in FIGS. 7 and 15, are included for the purpose of illustration and do not form part of the claimed invention.
